SHEET OF ELASTOMERIC MATERIAL OR SIMILAR ARTICLE

Granville H. Campbell, 2411 N. Cameron Ave.,
Covina, Calif.

Filed Sept. 26, 1962, Ser. No. 71,871

Term of patent 14 years

(Cl. D87—3)

The back of the sheet shown in the drawings is plain and unornamented.

I claim:

The ornamental design for a sheet of elastomeric material or similar article, substantially as shown and described.
